UNITED STATES PATENT OFFICE.

CARL AXEL WILHELM HULTMAN, OF STOCKHOLM, SWEDEN.

AUTOMATIC TELEPHONE-EXCHANGE SYSTEM.

1,250,885.

Specification of Letters Patent. Patented Dec. 18, 1917.

Application filed March 15, 1915. Serial No. 14,380.

To all whom it may concern:

Be it known that I, CARL AXEL WILHELM HULTMAN, director, a subject of the King of Sweden, residing at Jakobsbergsgatan 5 24, Stockholm, Sweden, have invented certain new and useful Improvements in Automatic Telephone- Exchange Systems, of which the following is a specification.

It has been proposed in order to diminish 10 the number of movable parts in automatic telephone exchange systems to use so-called connectors for up to 10,000 subscribers instead of—as is the case in some systems—connectors for only 100 to 200 subscribers. 15 By using such greater connectors the number of so-called selectors is reduced to a single one for up to 100,000 subscribers.

In such greater connectors, however, the inconvenience will arise, that in case the 20 wires of the subscribers are for instance arranged in groups, each containing 100 wires in width and 100 wires in height, the switching organ, movable in the connector and completing the coupling, must under certain 25 circumstances be moved up to 100 steps in the one and the same number of steps in the other direction, which will considerably delay the coupling.

This inconvenience will be avoided according 30 to the present invention which consists in arranging the subscribers' wires or their end contacts in groups and in arranging the switching organ in such a way in relation to said groups as to make it possible to move 35 the said organ to the one or the other of said groups. Suitably four groups are used, two on the right and two on the left hand of the switching organ, two of said groups being arranged under and two above the switching 40 organ.

For 10,000 subscribers four groups will in this way be obtained, each one containing the wires of 2500 subscribers, arranged in groups of 50 in width and 50 in height. In 45 this way the switching organ need not move more than up to 50 steps in the one and up to 50 steps in the other direction. On the other hand the motion will take place alternating to the right upwardly, to the right downwardly, to the left upwardly or to the left downwardly.

For obtaining the said different motions a number of devices will of course be necessary, which will in the following be more fully described.

The division in groups can of course be made in many different ways, as the relative position of the groups as well as their number can considerably be varied.

In the following the invention is described 60 as used in connection with an automatic telephone exchange system of the kind, where the subscribers' wires or ribs, connected thereto—uncovered or provided with contacts—are parallel and are arranged with interspaces, wherein the switching organs are movable. In such a system the invention is especially useful not only on account of the increased rapidity in the switching operation but also on account thereof that the 70 switching organs, which move between the wires, must be made as short as possible in order that a good and effective guidance thereof may be obtained. It is then of importance that the number of subscribers' 75 wires, arranged above each other, is not too great.

In the annexed drawings Figure 1 shows schematically a telephone exchange system according to the present invention.

Figs. 2 and 2^a and 2^b show a coupling diagram and Fig. 3 a diagrammatic view of a preferred embodiment of a device for moving the switching organ.

A is the switching organ and its corresponding mechanism and B¹, B², B³ and B⁴ 85 four groups of subscribers' wires E surrounding A. In connecting two subscribers the switching organ A will at first move to the right or to the left in the direction of 90 the arrow C¹ or C² and thereafter it will move upwardly or downwardly in the direction of the arrow D¹ or D², depending upon in which group the called subscribers' wires, ribs or contacts are situated.

The order of motion can of course be reversed, so that the vertical motion will take place at first and the horizontal motion thereafter.

From Fig. 1 the principal difference between the present system and known systems will be clear. The switching organ

and its mechanism has hitherto always been arranged as is indicated in dotted lines at A¹. For 10,000 subscribers, arranged 100x100, it has been necessary in order that A¹ should reach the subscriber highest to the right to move A¹ 100 steps to the right and thereafter to move it 100 steps upwardly; according to the present invention 50 steps to the right and 50 steps upwardly 5 are sufficient. By this construction the advantage is obtained that the switching operation consumes comparatively short time and that the motion of the switch is short and therefore more steady and secure. 10 In Figs. 2, 2^a and 2^b a coupling diagram is shown, showing in detail the connections in a system according to the invention. Before this diagram is described, it will be necessary to describe some of the most important switching elements. 15

A. The most important switching elements in the present telephone exchange system.

As in the most of the known telephone exchange systems a calling subscriber will at first operate a first preselector. The number thereof is quite the same as that of the subscribers; a first preselector is thus arranged for every subscriber. From this 25 first preselector the subscriber will then operate a vacant second preselector. The number thereof is for instance 1,000 if 10,000 subscribers are connected.

For the above named number of subscribers the number of selectors is suitably 35 500 to 600. In connection with each selector a reversing device and a register device is arranged. These devices will now be operated by the subscriber by means of the 40 usual finger disk arranged at the apparatus. The register device is operated by means of the finger disk and after it has been brought to the positions corresponding to the figure of the subscriber, the motion of the switching organ can take place. 45

If the number of subscribers is greater than 10,000, it is necessary to arrange for each of the 10,000 subscribers a so-called selector with connector-finder. It is not 50 suitable to arrange in each group, for instance B¹ in Fig. 1, more than 2,500 subscribers' wires. In Figs. 2^a and 2^b three connector-finders are shown, corresponding to a central with up to 30,000 subscribers. 55

In correspondence to the position of the register device the switching organ must move to the right or to the left, upwardly or downwardly, depending upon in which of the B-groups in Fig. 1 the called subscribers' 60 wires, ribs or contacts are located. This is performed by means of special relays, whereof the one or the other is operated depending upon the position of the register device. The said relays transmit the con-

nexion of the switching organ to machine-operated organs, movable to the right or to the left and upwardly or downwardly. It is also possible to arrange the connections in such a way that the relays transmit the motion of said organs in one or the other 70 direction.

In Figs. 2, 2^a and 2^b a and b are the two service lines. d is an auxiliary line. It is possible to make up a system wherein 75 the switching organ is operated by the aid of the d-line, but wherein all impulses are sent through the a- and b-lines.

It is, however, also possible to operate the switching organ alternating by the aid of the b- and d-lines, and to let all impulses 80 pass through the d-line and one of the speech lines. Such a system is shown in Figs. 2, 2^a and 2^b.

B. A switching system wherein the switching organ is operated by the aid of an auxiliary line and one of the speech lines.

Because the two preselectors over which the subscriber will reach the selector, are arranged in a known manner, perform a 90 known purpose and are of no importance at all for setting forth the present invention, they are not shown or described. From the second preselector are drawn the speech lines a and b as well as an auxiliary line d. 95

I. The selector.

When the second preselector has stopped, the subscriber has been connected to the selector and he can thus begin to operate his finger disk. The a-line of the subscriber is now connected with the line-relay LR₃ over the contact 21, the point x₂ and the rest contact in the 9th position of the first part I of the reversing devices O. The b-line of the subscriber is connected with the line-relay LR₄ over the contact 22, the point y₂, the contact 151 and the rest contact in the 9th position of the second part II of the reversing device O. 100 105 110

LR₃ and LR₄ are both connected with the battery BB.

The different contacts in O are hereafter marked I:9 or IV:6 and so on; this means 115 the contact 9 in the part I or the contact 6 in the part IV and so on. The four arms of I-IV are arranged on a common shaft bearing also a tooth wheel, operated by the electromagnet OE.

When the subscriber now sends current impulses on the a-line, they will excite LR₃ and the contact 23 is alternatingly opened and closed. Every time 23 is closed, the following circuit is closed: each, 23, I:1 (the reversing device in its first position) and the first register RE₁ to the battery. The register RE₁ (10,000-figure register) is 120 125 in this way moved a certain number of steps

corresponding to the first digit in the desired figure. When after the impulses on the *a*-line an impulse is sent on the *b*-line (the said impulse is automatically sent out 5 by the finger disk), the relay LR_4 is excited and the contact 24 is closed for a moment. Hereby the following circuit is closed: earth, 24, II:1, the upper coil OE of the electromagnet of the reversing device and the battery. The electromagnet OE is excited and when it is again released, the reversing device is moved to the second position. The subscriber will now again send impulses 10 upon the *a*-line, which will again operate the relay LR_3 . On account of the position of the reversing device O the said impulses are sent to the register RE_2 (1000-figure register) which will take the position corresponding to the second digit whereupon 15 the electromagnet of the reversing device quite as before will obtain an impulse and the reversing device will move to the third position.

In the same way the registers RE_3 (100-figure register), RE_4 (10-figure register) and RE_5 (unit-register) are operated and the reversing device will move step by step to its 6th position.

In this position the following circuit is 0 closed: earth, III:6, the relay UR and the battery BB .

Hereby the contacts 21 and 22 are released, *i. e.*, the subscriber's line is shut off from communication with the selector and this state will prevail also at III:7 and III:8. Besides a connection with earth is obtained over III:6 and the contact 25 of the register RE_1 to the magnetic clutch MK_2 of the selector. The said clutch is inserted 5 between the arm of the selector and its shaft, driven mechanically. The contact 25 was closed at the moment the register RE_1 left its rest-position. When the electromagnet clutch MK_2 is excited, the selector is in motion 10 mechanically and begins to rotate.

During this rotation the register RE_1 is moved step by step by its obtaining intermittent current impulses from the battery through the register RE_1 , over I:1 (the bottom contact) the outermost ring of the selector, the corresponding contact spring and the earth connection. In this way the register RE_1 will follow the rotation of the selector until it has reached the rest position 5 when the contact 25 is opened. Then the clutch electromagnet MK_2 will be released and the selector will stop. In this way the selector has been brought to a position, dependent upon the position the register RE_1 10 has obtained on account of the first series of impulses from the subscriber. The toothed wheel of the register RE_1 as well as the toothed wheel of the other registers is provided with 11 teeth; the selector on the con-

trary is provided with 10 earth-connections. 65 If the subscriber had only sent a single impulse in the first series, the register RE_1 has thus 10 steps to move before the normal position has been reached. The selector will thus rotate until it has passed 10 earth-connections and it will thus at this moment, when it stops, be connected to the first 10,000-figure group of subscribers. In case 70 the subscriber should have in the first series sent out 2 impulses, 9 earth-connections from the selector are necessary for bringing the register RE_1 back to the rest position, and the selector will then rotate until the next contact group from the last one is reached, corresponding to the second 10,000-figure 75 and so on.

When the register RE_1 has reached again its rest or initial position, the contact 26 is closed, whereby the following circuit is closed: earth, III:6, 26, the contact 152 and 80 through the start relay R_3 to the battery. As soon as the relay R_3 is excited, its contact 153 will be closed, whereby the following circuit will be closed: earth, 153, the clutch electromagnet MK_4 to the battery. 85

The said electromagnet, which when excited will connect the arm of the connector-finder with the mechanically operated shaft *ak*, will thus obtain current in the above way and the connector-finder will begin to rotate and will continue its rotation until a vacant connector is found, that is until in the engaged part of the connector-finder an earth-connected *c*-contact is found. At this moment current will be obtained through 90 the test relay LyR_3 along the following way: the battery, the contact 154 of R_3 , LyR_3 , the long *d*-rib of the selector, the corresponding *c*-contact to the engaged test-plate in the selector and further over the connection with the corresponding section of the connector-finder and over a contact in this section to earth through a resistance coil R_4 . The relay LyR_3 is thus excited and its contact 152 is released, whereby the relay R_3 100 will be released. Hereby the contact 153 is released and the electromagnet MK_4 will also be released, this causing the connector-finder to stop. While the relay LyR_3 was 105 excited, its contact 155 was closed so that the greater part of LyR_3 was shortcircuited and battery is now cut in over 155 and the contact 156 in the selector (closed as soon as the selector leaves its initial position) instead of over the contact 154 of the relay R_3 110 (this contact was for the rest opened the moment after LyR_3 had been excited). By the shortcircuiting of the greater part of the relay LyR_3 nearly the full battery tension 115 will be obtained on that *c*-line, which corresponds to the connector as selected; the said connector will thus be marked engaged. A test relay (LyR_3) belonging to a connector-

120

125

finder, rotating for finding or selecting a vacant connector cannot be excited by the very low difference in tension, which this relay will obtain, when the one end contact 5 thereof is directly connected with the battery (over the contact 154) while the other end contact is connected with the *c*-contact, whose tension is only a very little lower on account of the shortcircuiting of the greater 10 part of a test-relay, as stated above. When the relay R_2 was excited, its contact 157 was closed whereby the current could pass through the electromagnet OE and when the relay R_2 is released when the connector- 15 finder has stopped, the reversing device will move into its 7th position.

II. The connector.

As soon as the selector has in the way described above selected a connector belonging to that 10,000-figure of subscribers' wires, corresponding to the first digit in the figure desired by the calling subscriber, the switching organ of this connector is to be 25 moved for selecting the line in question.

a. The horizontal motion of the switching organ.

In conformity with the number of impulses 30 which the subscriber had sent out for the second digit in the desired subscriber's figure, the register RE_2 had been brought to rotate a greater or less number of steps. The cam g^1 will hold the contact 32, controlling 35 the motion of the switching organ to the right or to the left, closed during the first to the fifth step of RE_2 .

We assume, in the first case, that the second series of impulses from the subscriber's 40 apparatus has been for instance 9; the contact 32 will thus be released. When the reversing device after the register RE_1 , having been restored moved to the 7th position, the following circuit was closed: earth J_2 , 33 on 45 the register RE_3 (was closed when RE_3 left its initial position), IV:7, the electromagnet $O_2 E_2$ and the battery. The said electromagnet will consequently be excited. On the closing of its contact 158 the following 50 circuit will be closed: earth, 33, IV:7, 158, 159 of the electromagnet V , the long *d*-rib of the selector and over the engaged *d*-contact of the long *d*-rib in the selected section of the connector-finder and further over the *d*- 55 line to the selected connector and finally over the starting relay $S_1 R_1$ over the contact 160 and the contact 161 (of the back relay BR_1) to the battery. $S_1 R_1$ will suitably be excited and its contact 162 will be 60 closed, whereby the following circuit will be obtained: the battery, 162, the clutch electromagnet $M_1 K_1$, the bottom winding of the auxiliary relay HR_1 and earth. When $M_1 K_1$ is hereby excited, the switching organ

will be moved to the right between B_2 and B_4 in Fig. 1 for selecting the 100-figure within which the called subscriber's line is located.

It is to be observed, that the relays $S_1 R_1$ and $S_1 R_2$ are at work only when the switching organ is to be moved to the right or to the left and that they will control the horizontal motion of the said organ. The relays $S_2 R_1$ and $S_2 R_2$ on the contrary will control the vertical motion of the switching organ.

The clutch, electromagnets and their manner of controlling the motion of the switching organ will be described at the end of the specification in connection with the description of Fig. 3.

At the beginning of the just named motion of the switching organ the contact 160 is released, but this is without any influence upon the current through the relay $S_1 R_1$, since $S_1 R_1$ on being excited had been connected with battery over its own contact 163 and the contact 164. $M_1 K_1$ being excited, its contact 165 is closed, whereby the *b*-line is connected to the long *b*-ribs for the horizontal and the vertical motion. The corresponding long *a*-ribs are in permanent connection with the *a*-line to the selector. For the sake of space the ribs *a* and *b* of the connector are in this scheme placed horizontally, though of course one series must be placed horizontally and the other vertically.

During the continued motion of the switching organ the slip springs S_1 will intermittently connect the *a*- and *b*-lines with earth, while one of two mutually connected springs slips respectively upon the long *a*- and *b*-ledges and the other upon ledges, provided with grounded plates. In the present case at first a grounding on the *a*-line will be obtained, which will pass over the connector-finder the selector, x_2 , the rest contact in I:9 through the relay LR_3 to the battery. When the relay LR_3 is excited 23 is closed whereby a circuit is obtained from earth over 23, I:7, I:2, RE_2 and to the battery, 110 whereby the register RE_2 is put in motion and will thus turn a step. When RE_2 on account of the current impulses from the subscriber has turned 9 steps and on account of the just named grounding on the *a*-line has 115 turned another step, it will remain a further step, until the register RE_2 has reached its initial position.

After the grounding on the *a*-line 10 groundings on the *b*-line will be obtained and 120 these are transmitted over the connector-finder and the selector over the point y_4 , 166 on V and over IV:9 through the relay LR_4 to the battery. (The circuit over 151 on UR is broken, as UR is continually excited). 125 The relay LR_4 will thus obtain 10 current impulses and its contact 24 be closed as many times. The groundings, hereby obtained,

which should be transmitted over 24, II:7, the contact 44 of RE_2 and through RE_3 to the battery, are however not obtained, as long as 44 is released, it is as long as the register RE_2 has not as yet returned to its initial position. After the ten groundings on the *b*-line another grounding is obtained upon the *a*-line and this grounding is in the same way as before transmitted to the relay LR_2 , whereby RE_2 is brought to turn further a step so that it has reached its initial position and 44 will thus be closed. The following impulses on the *b*-line can consequently now operate the register RE_3 and bring it to its initial position. At the moment this occurs, its contact 33 will be released, whereby that grounding will cease, which has over it controlled partly the relay $O_2 E_2$ and partly over 158 on $O_2 E_2$ and over the selector and the connector-finder the relay $S_1 R_1$ of the connector. When $S_1 R_1$ is released, the contact 162 is released, which will also release the electromagnet $M_1 K_1$ and the horizontal motion of the switching organ will cease. As the relay HR_1 is put in series with $M_1 K_1$, HR_1 will be released at the same moment as $M_1 K_1$. When HR_1 was excited at the beginning of the motion, its contact 167 was closed, whereby current was obtained from the battery over 167 through the clutch electromagnet MB_1 to earth. Hereby the switching organ was free to move horizontally but will be locked when MB_1 is released at the moment 167 is released at the relay HR_1 reaching its position of rest.

By the closing of the contact 167 a circuit will be closed over battery, 167, the relay R , the contact 168, to earth. This contact was closed at the moment the horizontal motion began. R will thus be excited and will upon the closing of its contact 169 obtain an exciting current, while the battery will be switched to the relay over 169 and 64 of the releasing magnet AR_3 of the connector, which will cause R to be excited even after the releasing of 167 on HR_1 . That the relay R has been excited is, however, of no importance during this phase of the switching operation, but is of importance when hereafter the disconnecting of the subscribers takes place. Upon the energization of HR_1 , its contacts 170—171 and 172 were released, preventing respectively $S_2 R_1$, $S_2 R_2$ and the back relay BR_2 from being operated. As before stated, the relay $O_2 E_2$ of the selector was operated at the moment when the reversing device O reached its 7th position and hereby the contact 173 was closed, whereby the following circuit was closed: earth, 173 and the top winding of the electromagnet OE to the battery. OE will thus be excited and when afterward the contact 173 is released at the moment when the register RE_3

reaches its initial position, that is at the moment the horizontal motion of the switching organ ceases, the reversing device O will turn to its eighth position. 65

The just described operations take place if the second digit in the called subscriber's figure had been 6—0. Should, however, the said digit have been for instance 2 the register under the action of the second series of current impulses from the subscriber turned two steps and consequently the cam g_1 would have held the contact 32 closed. In consequence hereof at the moment the reversing device after a vacant connector had been found had reached its 7th position, the following circuit would have been closed: earth 32, IV:7 (the inner contact) and over the relay V to the battery. This relay will thus be excited simultaneously with the relay $O_2 E_2$ as has hereinbefore been described by the closing of the contact 33 on RE_3 . When V is excited, its contact 174 is closed and hereby the following circuit is closed: earth, 33, IV:7 (the outer contact), 158 (of $O_2 E_2$), 174, the point y_4 and over the selector and the connector-finder the *b*-line to the connector and over its relay $S_1 R_2$ and over the contacts 175 and 161 to the battery. In consequence hereof in this case the relay $S_1 R_2$ will thus be operated instead of $S_1 R_1$ and this will cause the switching organ to move to the left instead of to the right as before described. When namely $S_1 R_2$ is excited its contact 176 will be closed, whereby the following circuit is closed: the battery, 176, 100 $M_1 K_2$ and the upper winding of HR_1 to earth. $M_1 K_2$, which will control the motion to the left, will thus be excited and the switching organ will begin to move to the left. 105

The contact 177 being closed the long *b*-ribs in the connector will be connected to the *d*-line and the said ribs will on account hereof be connected to the relay LR_4 over the connector-finder and the selector, the contact 178 of V (closed when V was excited) and IV:9. The *a*-ribs of the connector will as before be in connection with the relay LR_3 . When the switching organ begins its motion to the left, at first 6 impulses are sent out on the *a*-line and as before the register RE_2 will turn 6 steps. After these 6 steps the register RE_2 will be in its 8th position. The contact 32 was released already in the 6th position, but in spite hereof V will continue to be energized, while it is continually energized by a current over its contact 179 as long as $O_2 E_2$ is energized. After the 6 impulses on the *a*-line 10 impulses will be transmitted on the *d*-line and the relay LR_4 will consequently be energized 10 times without operating the register RE_3 while 44 of the 115 120 125

register RE_2 will continue to be released: After the said 10 impulses a further impulse is transmitted through the a -line and thereafter further a series of 10 impulses 5 on the d -line, which will continue to have no effect upon the register RE_3 . In this way it will continue until RE_2 after the 9th impulse has reached its initial position, whereafter the impulses upon the d -line 10 will operate RE_2 . At the moment RE_2 reaches its initial position and its contact 33 is released $O_2 E_2 W$ and $S_1 R_2$ will be released and the motion of the switching organ will cease.

15 All the functions as has been described above for the other case, of the relays, which also in this latter case are operated, are in this case of the same importance and the contact 180 of $S_1 R_2$ has the same task to 20 operate this relay as 163 has in relation to the relay $S_1 R_1$.

b. The vertical motion of the switching organ.

25 The horizontal motion having now been completed and the reversing device of the selector having reached its 8th position, the vertical motion is now to begin. At the moment O has reached the 8th position, the 30 following circuit will be closed: earth, the contact 51 of RE_5 , IV:8 (the outer contact) and $O_2 E_2$ to the battery. $O_2 E_2$ will thus be excited even now in the same manner as during the horizontal motion and V will 35 also eventually be energized, dependent upon the position of RE_4 , that is if the contact 50 is closed or not. We may assume, that this is not the case and that V thus will not be energized. By the closing of 40 the contact 158 of $O_2 E_2$ the current is as before transmitted from earth over 51, IV:8, 158, 159, the selector and the connector-finder over the d -line to the connector and there over the contact 170 of the 45 relay HR_1 through the relay $S_2 R_1$ to the battery over the contacts 181 and 161. The relay $S_2 R_1$ will thus be energized and will be continually energized by a current over its own contact 182, which will cause that 50 this relay is energized also after the contact 181 has been released at the beginning of the vertical motion. The contact 183 of the relay $S_2 R_1$ being closed, current will flow through the clutch electromagnet M_2 , K_1 and the upper winding of the relay HR_2 , the said two electromagnets being thus energized. The switching organ of the connector will consequently begin to move upwardly and quite in the same way as on the 55 horizontal motion groundings will be obtained on the a - and b -lines said groundings moving the registers RE_4 and RE_5 to the initial position. The contact 184 of $M_2 K_1$ has the same function as 165 of $M_1 K_1$

namely to connect the long b -ribs of the 65 connector with the b -line.

When the relay HR_2 was excited, its contact 185 was closed, whereby the clutch MB_2 was released, so that the vertical motion can freely take place and when 185 is afterward released, the clutch is again operated 70 for securing the switching organ. The closing of the contact 186 will energize the test relay LyR_4 , so that it will be energized 75 during the whole vertical motion. The releasing of the contact 187 is arranged in order that the c -contact of the switching organ, which will during the vertical motion slip on the wires in the group, shall not disturb eventual speeches between other subscribers and the releasing of 188 will cut away the ringing relay RR from function. 80

The relay LyR_4 is energized during the entire vertical motion and the contact 250 is closed and therefore the c -contact which 85 slips on the wires in the group, could disturb eventual speeches, but when the relay HR_2 is energized, its contact 187 is released and the c -contact (shown at the right of Fig. 2^b) cannot disturb existing connections. 90 The contact 188 will cut out the ringing relay RR .

In case the contact 50 of the register RE_4 should have been closed by the action of the cam g_2 , the switching organ would of 95 course have moved downwardly instead of upwardly for the same reason that caused the horizontal motion, when 32 on the register RE_2 was closed.

When the connector is arrested on the 100 terminals of the wanted line, the relay HR_2 deenergizes and opens the circuit of the test relay LyR_4 at contact 186 and if the wanted line is idle, the relay LyR_4 is deenergized.

The ringing relay RR is energized over 105 contacts 191, 161 and connects the ringing generator to the wanted line over the contacts of the test relay LyR_4 . When the called subscriber answers, the relay AR_3 disconnects the ringing-relay at contact 65, 110 and at contact 64 opens the locking circuit of relay R , which therefore deenergizes.

If, however, the wanted line is busy, the test relay LyR_4 remains energized over contacts 250, 187, 217 and the ground on the 115 test terminal of the wanted line. The application of ringing-current to the wanted line is therefore prevented, and a busy interrupter T_4 is connected over contact 219 to a third winding on the relay AR_3 , whereby 120 busy signaling currents are transmitted to the calling subscriber.

c. The mechanical operation of the switching organ.

The switching organ is arranged upon a carriage or the like, bearing the slip springs S_1 and moved horizontally upon a rib or

the like. The said slip springs will slip upon the two horizontal *a*- and *b*-ribs of the connector.

The horizontal rib can in its turn be moved in the vertical direction by bearing in its ends carriages, sliding on horizontal ribs and bearing the slip springs S_2 , slipping upon the upper long *a*- and *b*-ribs, which are in Fig. 2 shown horizontal, but which lie in the vertical direction.

Fig. 3 is a schematic view of a preferred embodiment of a device for moving the switching organ after the electromagnetic clutches $M_1 K_1$, $M_1 K_2$, $M_2 K_1$ and $M_2 K_2$ have been excited.

e_1 and e_2 are two shafts rotating in opposite directions and bearing rope pulleys or the like f_1 and f_2 , over which the endless rope h passes. The rope pulleys f_1 and f_2 can move freely on the shafts and can by means of the electromagnetic clutches $M_1 K_1$ or $M_1 K_2$ be coupled to the shafts.

A rack bar i is in such a way connected with the rope h that the bar can be moved vertically but not horizontally in relation to the rope. This cog bar i which bears two switching organs, the one directed downwardly, the other upwardly, meshes with a pinion k , displaceable but not turnable on the shaft l , which by means of the bevel wheels m_1 , m_2 and m_3 , m_4 is connected to the shafts e_3 and e_4 , rotating in opposite directions.

The cog-wheels m_1 and m_3 turn freely upon the shaft l , but can by the aid of the clutches $M_2 K_1$ and $M_2 K_2$ be joined to this shaft.

The pinion k moves horizontally along shaft l with the rack bar.

Assume that the shafts e_1 , e_2 , e_3 and e_4 rotate in the direction of the arrows, the switching organ will at the excitation of the clutch $M_1 K_1$ by the action of the rack bar i together with the pinion k be moved to the right, as has before been described. At the moment the motion is finished, the clutch MB_1 will be excited, so that the motion will be surely and momentarily stopped.

Should vertical motion clutch $M_2 K_2$ be excited, the rack bar i will descend and the switching organ arranged thereon will move downwardly as has been described above. When the motion is finished, MB_2 will be operated.

55 Claims:

1. Selective switching apparatus comprising stationary terminals so arranged as to be identified in a two coördinate system, a switch member having selective movement in the two principal directions of said coördinate system, means for setting said member, means for causing said member to be set from a starting position to one side in a principal direction and means for causing

said member to be set from the same position to the opposite side in the same principal direction.

2. Selective switching apparatus comprising stationary terminals so arranged as to be identified in a two coördinate system, a switch member having selective movement in the two principal directions of said coördinate system, means for setting said member, means for causing said member to be set from its normal position to either side in one principal direction and means for causing said member to be set from an intermediate position to either side in the other principal direction.

3. Selective switching apparatus comprising a number of groups of stationary terminals so arranged as to be identified in a two coördinate system, a switch member having selective movement in the two principal directions of said coördinate system and located normally in a central position relatively to said group of terminals, means for setting said member, means for causing said member to be set from a starting position to one side in a principal direction and means for causing said member to be set from the same position to the opposite side in the same principal direction.

4. Selective switching apparatus comprising four groups of stationary terminals so arranged as to be identified in a two coördinate system, a switch member having selective movement in the two principal directions of said coördinate system and located normally in a central position relatively to said groups of terminals, means for setting said member, means for causing said member to be set from its normal position to either side in one principal direction and means for causing said member to be set from an intermediate position to either side in the other principal direction.

5. Selective switching apparatus comprising stationary terminals in the form of parallelly extending, uncovered wires, so arranged as to be identified in a two coördinate system, a switch member having selective movement transversely to said wires in the two principal directions of said coördinate system, means for setting said member, and means for causing said member to be set from a starting position to either side in a principal direction.

6. Selective switching apparatus comprising four bundles of parallelly extending uncovered wires so arranged as to be identified in a two coördinate system, switch members having selective movement transversely to said wires in the two principal directions of said coördinate system and located normally in a central position relatively to said bundles of wires, machine driven means for setting said members, means for causing

each member to be set from its normal position to either side in one principal direction and means for causing each member to be set from an intermediate position to either 5 side in the other principal direction.

7. Selective switching apparatus comprising stationary terminals so arranged as to be identified in a two coördinate system, a switch member having selective movement 10 in the two principal directions of said coördinate system, means for setting said mem-

ber, a register device for controlling the setting of said member, and means for causing the said member to be set from a starting position to either side in a principal direction. 15

In testimony whereof I have affixed my signature in presence of two witnesses.

CARL AXEL WILHELM HULTMAN.
